COMBINATION CHECK VALVE AND FLASH ARRESTER

Woodrow S. Boedecker, Chicago, Ill., assignor to
The Bastian-Blessing Company, Chicago, Ill.,
a corporation of Illinois

Application March 23, 1945, Serial No. 584,332

8 Claims. (Cl. 48—192)

1

This invention relates to a safety device such as a flash arrester used in conjunction with equipment dispensing acetylene gas or oxygen.

In handling acetylene or oxygen the danger of dissociation or back fire through the system is always present due to the temperament of acetylene and its high flame propagation and to the oxidizing ability of oxygen if there is any trace of a fuel or ferrous material in the line.

In order to prevent any flame or pressure wave from reaching the storage tank in which such gases are stored, flame arresters have been designed which either add to the hazard unintentionally by becoming defective in use and creating a false impression of safety or are inadequate for extreme conditions. Other flame arresters materially retard the flow of gas under heavy load conditions or, if designed to handle heavy load conditions, are too bulky to be managed conveniently.

Not only does the present invention overcome these difficulties but it also checks the pressure wave which very often accelerates the activity of the flame wave. In fact, in some instances if the pressure wave, which precedes the flame wave slightly, can be checked, the flame wave can be brought under control before any definite hazard is created. On the other hand very often the flame wave starts very close to the tank and the interval of time between the pressure wave and the flame wave is so small that there is not enough time to check the pressure wave before the flame wave has done a great deal of damage.

One of the objects of the present invention is to control both the flame wave and pressure wave regardless of where the flame originates.

The invention is further characterized by a construction in which a pressure wave which has been able to get past the flame arrester can be brought under control without danger of the pressure wave generating a secondary dissociation or reaction.

These being among the objects of the present invention, other and further objects will become apparent from the drawing, the description relating thereto and the appended claims.

In the drawing:

Fig. 1 is a side elevation of a tank and manifold system for use with blowpipes in which the invention is incorporated;

Fig. 2 is a longitudinal section through the flash arrester assembly connected to the outlet of the cylinders illustrated in Fig. 1;

Fig. 3 is a section taken upon the line 3—3 in Fig. 2;

2

Fig. 4 is a modification of the embodiment illustrated in Fig. 2, and

Fig. 5 is a section taken upon the line 5—5 in Fig. 4.

Referring to Fig. 1, two high pressure cylinders 30 are shown as provided with shut-off valves 31 at the top thereof to which are connected embodiments of the present invention comprising a flash arrester 1 by means of a coupling 32. The downstream side of the flash arrester 1 is connected by pigtailed 33 to shut-off valves 34 in a manifold 35.

At the point where gas is removed from the manifold 35, a T 36 is provided leading to a container 37 serving as a water seal which in some measure is an additional safety factor between the point of use where the gas is used and the manifold. The outlet 40 of the water seal is connected to a two stage pressure reducer 41 by a coupling 42 and the outlet of the regulator leads to a point of use such as blowpipes through a conduit 43.

The flash arrester 1, as herein shown, comprises a bonnet 2 threaded as at 3 to receive a mating connection. A threaded passage 4 conducts gas in the connector 32 to a ball check 5 to compress a spring 6 of the ball check into a retainer 7 under the effective high pressure of the incoming gas.

The retainer 7 is threaded into place upon the same threading receiving the bonnet 2 as at 10 and is provided with passageways 8 therethrough to permit the gas admitted through the check valve 5 to flow through the retainer 7 to a cartridge 12 held in place by a circular lip 11. With the cartridge held against a shoulder 13 provided in a housing 9 at the base of a cavity 14.

Upon the cartridge 12 a second check valve 15 is provided setting upon a conical seat 16 formed in the housing 9 as held normally closed by a compression spring 17 which is supported in a cavity 18 upon a second bonnet 20 threaded into the housing 9 as at 21. The inner end of the second bonnet 20 and the space around the valve seat 16 define a valve compartment 22 for the gas admitted thereto upon the compression of the spring 17 by pressure of the gas exerted on the upstream side of the check valve 15. The valve compartment 22 is in communication with the pigtail 33 through passages 24 drilled through the second bonnet 20.

A normal flow of the gas is designated by an arrow 25. The ball checks 5 and 15 are pushed away from their respective conical seats under the pressure exerted upon them by the incoming gas.

which may be as high as 3000 pounds per square inch in case of oxygen or approximately 250 pounds or 300 pounds per square inch in the case of acetylene. The compression springs 6 and 17 are such that there is little opposition to the flow of gas, these springs being light enough for a sure closing of the valve under rest conditions.

The filter 12 is made up of a sintered porous metal, sand or silicon base or stone core 26 held in place at both ends by retaining screens 27 and 10 reinforcing reticulated plates 28 closing the two ends of a cylindrical shell 29 forming the side wall mating with the cavity 14.

The shell 29 and reticulated reinforcing end plates rigidify the form cartridge against suddenly applied pressures. The screens 27 prevent dirt or other formed material from passing through the filter or entering the filter, while the core 26 serves to spread out the flow of gas through small interstices to follow route channels which bring the gas into intimate contact with the material both to cool it and retard any sudden or excessive flow.

The porosity of the core 26 may be varied to some degree depending upon the size of the core and its flow area. A convenient size to handle is a cylindrical form $\frac{1}{2}$ inch long and one inch in diameter with the core made of porous iron of a density within the range of 2.50 grams/cubic centimeter to 2.85 grams/cubic centimeter to provide a flow of acetylene of from 140 cubic feet per hour for the 2.50 density to 40.7 cubic feet per hour for the 2.85 density. If greater flow is required, the diameter of the core can be increased, the densities given or equivalent criteria being otherwise safely capable of snuffing out flames when flash-backs occur. Density as rated here is based upon the factor 7.85 grams/cubic centimeter as being the density of a solid body of iron and 2.50/7.85 being the percentage of density of the filter core. When other metals than iron are used, the ratio of the density of the sintered core to the density of the solid metal is maintained within the limits of 2.50/7.85 and 2.85/7.85.

In the event of a flash back in the manifold 35 which results either in a flame wave or a pressure wave moving towards the cylinders 30, the check valve 15 will be the first to be affected. If the wave originates close to the check valve, the valve 15 may not close before a substantial amount of pressure enters the cavity 14. From this cavity it backfires through the filter but by this time the pressures on both sides of the check valve 15 are equalized gradually and the check valve 15 has more time to close before any high pressure is effected thereagainst. Once the check valves are closed there is no opportunity for the flame or pressure wave to enter the connector 32. The only thing that can happen is that the surge of the gas flowing from the cylinders is suddenly stopped. However, the parts are made strong enough to take care not only of the pressures present in the cylinder but also of higher pressures expected in them.

The filter has the effect upon any backflow of gases of cooling them below their ignition point and also separating them into such small channels that any flame present is snuffed out.

In the embodiment illustrated in Fig. 4 the check valve 15 is bypassed by two small passageways 45. It has been found that this slight bypassing with very small passages such as are provided by a 60 to 70 drill has the advantage in handling oxygen and acetylene of relieving any dangerous shock waves which might have a shat-

tering effect upon the parts, these passageways serving more or less as safety valves which cushion the shock but without permitting enough back pressure to be applied against the filter to cause damage. In fact the embodiment illustrated in Fig. 4 can be used as a standard flash arrester for even low pressure passages since the bleed passages 45 are small enough to inhibit materially the passage of flame as well as pressures in event the flash arrester is used with acetylene installations.

Having thus described the apparatus and the embodiments of the invention it will be apparent from the description how the objects and processes of the invention are accomplished. However, since in some respects it is not possible to account fully for the improved results which are obtained by the invention, it should be understood that any attempt to analyze the theory which is believed to be responsible for these results is to be construed not as defining a mode of operation but merely as a possible explanation of certain physical and metallurgical phenomena which have been observed.

Consequently, although certain preferred embodiments of the invention have been shown and described therein, it will be apparent to those skilled in the art that various uses, modifications and changes can be made without departing from the spirit and substance of the invention, the scope of which is commensurate with the appended claims.

What is claimed is:

1. A device of the class described comprising a housing having a passage for normal movement of gas under pressure therethrough in one direction, a porous cartridge in said passage said cartridge being formed of sintered powdered metal having a density such that the ratio of fluid density to the density of solid metal falls within the limits 2.50/7.85 and 2.85/7.85, and a back flow normally closed check valve in said passage upon the downstream side of said cartridge to protect it initially against wave shock.

2. A device of the class described comprising a housing having a passage therethrough threaded at both ends, a porous sintered metal cartridge in said passage approximately one inch in diameter and one-half inch thick having such flow characteristics as to pass between 40.7 and 140 cubic feet of acetylene per hour, means for re-enforcing said cartridge against disintegration including a perforate retainer threaded into one of said openings and having a recess therein, a normally closed spring loaded check valve member in said passage upon the retainer side of said cartridge for obstructing the flow of gas except in one direction, said spring being received in said recess, and closure means for said one of the openings having a seat cooperating with said check valve member.

3. A flash arrester for use between a high pressure gas cylinder and a manifold comprising a housing having a passage therethrough, a porous material disposed in said passage whose porosity is minute enough to snuff flame from highly combustible gases passing therethrough, a check valve received in said passage for obstructing the back flow of gas, and bleeder means for bypassing the check valve from one side thereof to the other including a bleeder passage through said housing of a size within a range of 60 to 70 drill size.

4. A device of the class described comprising a housing having a passage therethrough divided by an integral flange defining a valve seat and terminated in enlarged threaded openings, a po-

rous cartridge received in one of said openings, a retainer holding said cartridge in place, a pair of closures, one threaded into each of said openings, a check valve member cooperating with said valve seat and received within one of said closures, a second check valve member cooperating with a valve seat on the other of said closures, and means including passageways through said closures for connecting the housing to a gas cylinder and a manifold.

5. A device of the class described comprising a housing having a passage therethrough threaded and enlarged at one end to define a cavity and threaded and shouldered at the other end to present a valve seat, a porous cartridge in said cavity, means for holding the cartridge in place threaded into said one end, and a check valve disposed into the other end to cooperate with said valve seat to obstruct flow of gas through said cartridge except in one direction, means for by-passing the valve seat including a bleed passage less than .05 of an inch in diameter, said bleed passage extending from a point on one side of said valve seat to a point on the other side thereof.

6. A device of the class described comprising a housing having a passage therethrough threaded and enlarged at one end to define a cavity and threaded and shouldered at the other end to present a valve seat, a porous cartridge in said cavity, means threaded into said one end for holding the cartridge in place including a perforate retainer and a closure having a second valve seat thereon, a check valve member cooperating with said second valve seat, and another check valve member threaded into the other end to cooperate with said first mentioned valve seat, said check valves cooperating to obstruct flow of gas through said cartridge except in one direction.

7. A device of the class described for use in a high pressure connection between a high pressure cylinder and a manifold ahead of a pressure reducer, comprising a housing having a passage

therethrough threaded and enlarged at one end to define a cavity upon one side of a wall and threaded and shouldered upon the other side of the wall to provide a valve seat surrounding a passage through the wall, a perforate element supported in the cavity in spaced relation to the wall, a porous cartridge of sintered metal in said cavity resting against said element, means threaded into said one end for holding the cartridge in place including a perforate retainer and an adaptor having a check valve therein, a second check valve supported in the other end to cooperate with said valve seat, said check valves cooperating to obstruct the flow of gases therethrough except in one direction, and means for by-passing said valve seat comprising a bleed passage through said wall less than .05 of an inch in diameter.

8. A filter for arresting flame comprising a sintered porous metal core having a density such that the ratio of said density to the density of solid metal is within the limits 2.50/7.85 and 2.85/7.85, dirt screens at both ends, reinforcing reticulated plates holding the screens in place, and means for sealing the sides of the core from dirt.
